I. KRESH

CASH REGISTER ATTACHMENT

Filed April 6, 1923

INVENTOR.

Irving Kresh.
Richard B. Owen
ATTORNEY.

UNITED STATES PATENT OFFICE.

IRVING KRESH, OF BROOKLYN, NEW YORK.

CASH-REGISTER ATTACHMENT.

Application filed April 6, 1923. Serial No. 630,344.

To all whom it may concern:

Be it known that I, IRVING KRESH, a citizen of the United States, residing at Brooklyn, in the county of Kings and State of New York, have invented certain new and useful Improvements in Cash-Register Attachments, of which the following is a specification.

This invention relates to attachments for cash registers and the like and more particularly to a novel and improved currency detector whereby spurious bills may be examined during the interim of making change.

One of the objects of my invention is the provision of a transparent plate conveniently located on the frame or casing of a cash register, for instance, or within the drawer of the same, including provision whereby said plate will be illuminated from beneath when the drawer is opened so that a bill placed upon the plate can be carefully observed and the characteristic impressions noted to determine its legality during the act of returning change without notice or observation on the part of the customer presenting the bill.

Another object of my invention is the provision of a cash register attachment including a make and break circuit cooperating with the drawer of the register for illuminating an electric light or bulb placed beneath the transparent plate for the purpose of inspecting the bill presented during the act of making change.

With the above objects in view and others which will be more readily understood as the description proceeds and when taken in connection with the accompanying drawings,

Figure 1 is a side view of a cash register showing the invention.

Figure 2 is a cross section showing the invention and its relation to the cash drawer.

Figure 3 is a top plan partly in section, showing the relative arrangement of the transparent plate with the globe and the connector.

Figure 4 is a section taken on the line 4-4 of Figure 2.

Referring now to the drawings wherein like reference characters designate corresponding parts throughout the several views, 5 designates generally the casing of

a cash register or the like and 6 the keys thereof, which, when depressed automatically operate and permit the cash drawer 7 to slide outwardly as indicated by Figure 1 of the drawing. On the ledge or front shelf 8 of the register and intermediate the sides thereof, I have provided a transparent plate 9 preferably of glass, which is of a length slightly longer than the conventional size of legal tender, such as a 1, 5, 10 or 20 dollar bill. The plate 9 is also of a width slightly wider than the bill and as shown, is provided with a flanged portion 10 which is seated in a recess or cut out in the shelf 8 and secured thereto by the fastening element 11 as clearly shown. While I have illustrated and shown the transparent plate 9 as positioned on the shelf or ledge of the register casing, it should be realized that the transparent plate might be connected in various other manner to the framework or if so desired, may be installed directly in a compartment in the cash drawer 7. Under ordinary circumstances, in examining currency, a magnifying glass is also used and while the same is not shown, it may be attached to the casing or the side of one of the compartments in the drawer for use in connection with the illuminated transparent plate 9.

Secured to the side of the ledge or shelf 8, I have provided a plate 12, having a socket 13 to which an elliptical bulb 14 is attached by the bayonet slot 15. The connectors 17, 18, leading to the socket and to the battery (not shown), are connected to the contact plates 19, 20, which plates cooperate with a contact plate 21, on the top edge of the sliding drawer. It will thus be seen that when the drawer is opened, contact will be effected and the bulb 14 will be illuminated and on the other hand, when the drawer is closed, the circuit will be broken. Consequently, when presenting a bill to the clerk, the same is usually placed on the transparent plate 9 and as the keys 6 are depressed, the drawer will slide outward and the bulb 14 will be illuminated. During the act of making change, the clerk can closely examine the bill placed over the illuminated plate and its legality quickly determined as by closely examining the threads or other characteristic indicia on the bill as is well known.

While I have illustrated and described

my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claims.

10 Having thus described my invention, what I claim as new and desire to secure by United States Letters Patent is:—

15 1. In combination with a casing and sliding drawer of a cash register, a transparent plate, means for securing the said plate to the front of the casing, and an incandescent bulb positioned beneath said plate and

means for illuminating said bulb only when the drawer is opened.

2. In combination with the casing and 20 drawer of a cash register, a transparent plate, means for securing the plate to the front portion of the casing, a socket and an incandescent bulb therefor attached to the casing and beneath the plate, contacts and 25 conductors leading to the bulb and socket, a contact on the drawer in circuit with the conductors whereby the bulb will be illuminated only when the drawer is opened to permit of the observation of legal tender 30 placed on the said plate.

In testimony whereof I affix my signature.

IRVING KRESH. [L. S.]
